ARTHUR E. SMITH, OF LOS ANGELES, CALIFORNIA.

SYRINGE AMPUL.

Application filed October 26, 1927. Serial No. 228,915.

This invention relates to improvements in ampules or similar containers.

The general object of this invention is to provide a novel ampul including separate 5 chambers or compartments wherein dissimilar ingredients are preserved and wherein means is provided for allowing the ingredients to mix to form a desired product.

Another object of this invention is to provide a container including two compartments which are normally out of communication with each other, but which can be placed in communication with each other by a novel means wherein the separate compartments 15 have sealed therein the component parts necessary to provide a drug in solution.

A further object of the invention is to provide a glass ampul including a plurality of compartments wherein one compartment includes a vehicle for the drug and wherein the ampul includes a member for forcing the solution from the ampul.

Another object of the invention is to provide an ampul including two compartments, 25 one of which has a movable stopper therein and wherein a frangible member separates the two compartments.

A further object of the invention is to provide an ampul including two compartments 30 one of which has a drug therein and the other contains a vehicle, and wherein novel means is provided for allowing the drug and vehicle to mix and wherein each end of the ampul and the intermediate portion between 35 the two compartments is provided with a frangible neck portion which may be broken.

A specific object of this invention is to provide a novel ampul of the class described which is adapted when one compartment has 40 been removed to fit within a syringe for ejecting the mixed contents of the ampul.

A further object of the invention is to provide an ampul of the class described having means in the drug containing member 45 which is adapted to act as a piston to expel the mixed contents of the ampul.

A still further object of this invention is to provide a novel instrument for fracturing an ampul seal and for allowing a vehicle to 50 mix with the drug.

Other objects and advantages of this invention will be apparent from the following description taken in connection with the accompanying drawings wherein:

Fig. 1 is a central longitudinal section 55 through my improved ampul.

Fig. 2 is a view similar to Fig. 1 showing one end of the ampul broken away, the seal between the two compartments fractured and the vehicle mixed with the drug. 60

Fig. 3 is a side elevation of the drug containing compartment after the vehicle compartment has been removed therefrom and the tip broken off in readiness for use in a 65 syringe.

Fig. 4 is an enlarged fragmentary view of my improved ampul showing the metallic seal between the two compartments.

Fig. 5 is a view similar to Fig. 4 showing the metallic seal fractured. 70

Fig. 6 is an enlarged longitudinal section through a movable stopper.

Fig. 7 is a top plan view of the stopper shown in Fig. 6.

Fig. 8 is an enlarged view of the hollow 75 seal fracturing instrument.

Fig. 9 is a central longitudinal section of my syringe showing the improved ampul operatively positioned therein and showing the stopper of the ampul as being moved to eject 80 the contents of the ampul therefrom, and

Fig. 10 is a side elevation partly in section of my improved ampul after the contents thereof have been ejected.

Referring to the drawings by reference 85 characters I have indicated my improved ampul generally at 10. This ampul 10 as shown comprises two separate containers or compartments 11 and 12 which are preferably made of glass, fused together and constricted at their juncture as indicated at 13. 90

The end of the compartment 11 is closed by a bulbous portion 14 and at the juncture of the compartment 11 and the bulbous portion 14 a constricted portion is provided as indicated at 15. The end of the compartment 12 is provided with a tapered neck 16 which terminates in a closed tip 17. 95

Between the two compartments 11 and 12 at the constriction 13 a metallic seal 18 is 100 provided. This metallic seal is preferably a disk shaped platinum partition as clearly shown in Fig. 4 and is fused in position when manufacturing the ampul. In the compartment 12 and adjacent the constriction 13 I 105 provide a stopper indicated generally at 19 and shown in detail in Figs. 6 and 7. This stopper is preferably positioned in the compartment 12 before the tapered neck 16 and tip 17 are formed. Surrounding the tapered 110 neck 16 I provide a resilient collar 20 which is preferably made of a good grade of rubber.

- To render the bulbous portion 14 readily separable from the compartment 11 I preferably weaken the constriction portion 15 by scoring or etching it as at 21 (see Fig. 4).
- 5 To render the compartments 11 and 12 readily separable from one another I may weaken the constricted portion 13 by etching it as at 22 as clearly shown in Fig. 4 and to render the tip 17 readily separable from the neck 16
- 10 I may also weaken it by etching it just below the resilient collar as at 23.

The contents of the compartment 11 such as the vehicle 24 is preferably placed therein before the bulbous portion 14 is closed and the 15 contents of the compartment 12 such as the drug 25 is placed therein before the tip 17 is closed. Also, before the tip 17 is closed, the compartment is exhausted to a state of partial vacuum.

20 The stopper 19 is preferably made of a good grade of rubber and includes a body portion 28 having a protruding tip 29 extending therefrom. The stopper is shown as provided with a central recess 30 which terminates 25 short of the outer face of the tip 29. A groove 31, preferably bevelled, is provided at the juncture of the tip 29 and the body portion so that when the stopper is used as a piston to expel the contents of the ampul the 30 pressure exerted upon the stopper by the contents of the ampul will cause the lower edge of the stopper to tightly grip the inner side wall of the ampul and prevent any of the ampul contents from passing the stopper.

35 A metallic washer 32 is provided on the face of the stopper opposite the tip 29 and includes a central aperture 33 of approximately the same size as the recess 30. Depressed loops 34 may be formed in the washer by slitting and punching and are embedded in the material of the body portion 28 at the time of the moulding of the stopper 19. By provision of the loops 34 there is a piece of rubber 34' over each loop. These pieces 34' being integral with the stopper, hold the washer 32 in place.

To prepare my improved ampul 10 for use the bulbous portion 14 is broken off at the etching 21 and a stylus 35 is inserted through 50 the opening at the constriction 15.

The stylus 35 is shown in detail in Fig. 8 and preferably comprises a solid metal stem 36 having an enlarged collar 37 thereon adjacent one end. The end adjacent the collar 37 55 is formed to a point as at 38 and a recess 39 is provided in the stem which extends from the pointed end 38 to a point just above the collar 37. Apertures 39' are provided in the stem above the collar 37 and form communicating passageways from the exterior of the 60 stem to the recess 39.

When the stylus 35 has been inserted into the compartment 11 it is moved downward so that it fractures and passes through the 65 metallic partition, into the recess 30 of the

stopper, through the solid portion of the stopper tip 29 and into the compartment 12 as clearly shown in Fig. 2. When the stylus has sufficiently entered the compartment 12 it will be stopped by the collar 37 thereon 70 abutting the metallic partition 18 as clearly shown in Fig. 5. The collar 37 is so positioned upon the stem 36 of the stylus that when it abuts the metallic partition the end 38 is sufficiently clear of the stopper 19 to 75 allow the vehicle contained in the compartment to be drawn by the vacuum in the compartment 12 through the apertures 39', into recess 39 and be freely discharged into the drug compartment 12, thus mixing the vehicle 80 and the drug into a single solution.

After the vehicle and the drug have been mixed the stylus is withdrawn and the compartment 11 separated from the compartment 12 at the etching 22. The tip 17 is then 85 separated from the compartment 12 at the etching 23 and the compartment 12 is then ready for use as an ampul in a syringe.

In Fig. 9 I have shown the compartment 12 as positioned in a syringe indicated generally at 40. This syringe includes a barrel 41 provided at one end with a tip 42 to which a hypodermic needle 43 is adapted to be attached. The tip 42 of the syringe includes a tapered recess 44 into which the collar 20 on 90 the ampul is adapted to be positioned. The syringe also includes an operating member 45 which is slidable in the syringe barrel 41 and which comprises an ampul positioning member 46 and a plunger 47. The positioning member normally moves with the plunger 47 due to the pressure of spring tongues 46'. The plunger 47 includes an enlarged head 48 and a reduced tip 49 of approximately the same size as the size of the aperture 33 in the 95 ampul stopper washer 32.

When the contents of the ampul or compartment 12 are to be ejected it is inserted in the barrel 41 of the syringe so that the collar 20 is positioned in the tapered recess 44 of the tip 42 and then the operating member 45 is positioned in the syringe barrel 41 and moved towards the tip 42. As the operating member is thus moved the positioning member 46 engages the ampul and correctly centers it so that the plunger 47 will enter the ampul through the opening at the constriction 13 and will engage the stopper 19.

When the plunger 47 is in engagement with the stopper 19 the plunger head 48 abuts the metal washer 32 and the reduced tip 49 is positioned in the washer aperture 33 and the stopper recess 30.

Upon further movement of the operating member towards the tip 42 the plunger 47 125 will force the stopper 19 towards the tapered neck 16 of the ampul and cause the stopper to act as a piston to expel the contents of the ampul into the hypodermic needle 43.

The pressure required to move the stopper 19 to expel the contents of the ampul will wedge the collar 20 in the tapered recess 44 of the tip 42 and form a fluid tight seal between the end of the ampul and the syringe.

As shown in Fig. 10 it will be seen that when the contents of the ampul or compartment 12 is ejected the tip 29 of the stopper projects down into the tapered neck 16 and forces more of the contents of the ampul out than would be the case if a stopper having a plain underface were used.

From the foregoing description it will be apparent that I have provided a novel form of ampul which can be economically manufactured, which is simple in construction and highly efficient in use.

Having thus described my invention, I claim:

20 1. An ampul comprising a tubular member including two compartments, a drug in one compartment and a vehicle for the drug in the other compartment, means normally preventing communication between said compartments, said means being puncturable to enable said vehicle to pass into said drug compartment to make a solution and a solid movable member in said drug compartment for forcing the solution therefrom.

30 2. An ampul comprising a tubular member closed at each end and having a restricted part intermediate its ends, a thin frangible foil disc fused to said restricted part to provide two compartments and a stopper positioned in one of said compartments.

40 3. An ampul comprising a tubular member constricted and closed at each end and having a constricted portion intermediate its ends, a frangible metallic disc fused to the inner wall of said intermediate constricted portion to provide two compartments, and a stopper positioned in one of said compartments, said stopper having a recess therein.

45 4. An ampul comprising a tubular member closed at each end and having a partition to provide two compartments, one end of said ampul being formed into a tapered neck, a stopper positioned in said compartment having a tapered neck, said stopper containing compartment being exhausted to a state of partial vacuum and containing a drug, the other of said compartments containing a vehicle, said stopper being positioned between said drug and said partition.

55 5. In combination with an ampul, a stopper positioned therein, said stopper being made of resilient material and having a recess therein, said recess terminating short of one face of said stopper, a stiff washer secured upon the face of said stopper said washer having an aperture therein corresponding to said recess in said stopper.

60 6. An ampul comprising a tubular member having a stopper positioned therein, said stopper being formed of a resilient material

and including a body portion adapted to tightly engage the inner wall of said ampul, a tip protruding from one face of said body portion, a recess in said body portion extending to a point spaced from the outer face of said tip, a metal washer on the face of said body opposite to said tip, an aperture in said washer corresponding to the size of said recess in said body and means to hold said washer on said body.

75 7. A stopper for an ampul, said stopper being formed of a resilient material and including a body portion adapted to tightly engage the inner wall of an ampul, a tip protruding from one face of said body portion, a groove at the juncture of said tip and said body portion, said groove forming a feather edge at the periphery of said body portion, a recess in said body portion extending to a point spaced from the outer face of said tip, a washer on the face of said body opposite to said tip, an aperture in said washer corresponding to the size of said recess in said body and a plurality of depressed tongues on said washer, said tongues being embedded in said body.

8. An ampul comprising a tubular member constricted and closed at each end and having a constricted portion intermediate its ends and having a partition in said intermediate constricted portion to provide two compartments, a stopper positioned in one of said compartments, said stopper being formed of a resilient material and including a body portion adapted to tightly engage the inner wall of said ampul, a tip protruding from one face of said body portion, a conical groove at the juncture of said tip and said body portion, said groove forming a feather edge at the periphery of said body portion, a recess in said body portion extending to a point spaced from the outer face of said tip, a washer on the face of said body opposite to said tip, an aperture in said washer corresponding to the size of said recess in said body and a plurality of depressed tongues on said washer, said tongues being embedded in said body.

105 9. For use with an ampul having a partition therein, a stylus including an elongated body provided with a pointed end adapted to penetrate the ampul partition and a hollow portion adjacent to one end, means on said stylus to limit its movement through the partition, said hollow extending along the body and means remote from the pointed end of said body to provide communication between the hollow portion and the exterior of said stylus.

110 10. In a stylus, an elongated body having an open end and having a hollow portion communicating with said end, means on said stylus to limit its movement through an aperture, said hollow extending along the body and an aperture extending into and intersecting said

hollow portion to provide communication between the hollow portion and the exterior of said stylus.

11. An ampul comprising a tubular member having a partition intermediate its ends to provide two compartments, the end of one of said compartments being tapered and being closed by a tip, an end of the other of said compartments being restricted and closed by 5 a bulbous part, said tapered portion being circumferentially etched on its outer periphery to thereby render said tip readily breakable, a similar etched part at said restricted closed end of 10 said second mentioned compartment to thereby render said bulbous part readily breakable therefrom, another similar etched part at said intermediate constricted portion to thereby render said two compartments readily separable from each other, said tapered end of said restricted closed end of said second mentioned 15 compartment to render said bulbous part readily breakable and another similar etched part adjacent to said partition to thereby render said two compartments readily separable from each other, said tapered end of said first compartment having a resilient circumferential band disposed thereon adjacent the 20 said etching thereon.

12. An ampul comprising a tubular member having a constricted portion intermediate its ends, and having a frangible member on the inner wall of said intermediate constricted portion to provide two compartments, the ends of said compartments being closed, one of said compartments having a stopper positioned therein adjacent said constriction, said stopper being made of a resilient material and having a recess therein, said recess terminating short of the face of said stopper, a washer on the face of said stopper which is towards 30 said intermediate constricted portion, said washer having an aperture therein corresponding to said recess in said stopper.

13. An ampul comprising a tubular member having a constricted portion intermediate its ends, and having a frangible partition fused to the inner wall of said intermediate constricted portion to provide two compart-

ments, the end of one of said compartments being tapered and being closed by a tip, the end of the other of said compartments being restricted and closed by a bulbous part, said tapered portion being circumferentially etched on its outer periphery to thereby render said tip readily breakable, a similar etched part at said restricted closed end of 45 said second mentioned compartment to thereby render said bulbous part readily breakable therefrom, another similar etched part at said intermediate constricted portion to thereby render said two compartments readily separable from each other, said tapered end of 50 said first compartment having a resilient circumferential band disposed thereon adjacent said etching, said tapered end of said compartment having a stopper positioned therein adjacent 55 said intermediate constriction, said stopper being made of a resilient material.

14. An ampul of the class described comprising a body portion, means to close one end of said body portion, a stopper movable in 60 said body and normally located opposite to said closed end, said body between said closed end and said stopper being exhausted.

15. An ampul of the class described comprising a body portion having a neck terminating in a closed tip, a reduced portion at the end of said body opposite said neck, said ampul being constricted between said body and said reduced portion, a stopper in said body adjacent said constricted portion, said stopper being adapted to be moved in said body, a penetrable partition adjacent said reduced portion, said stopper having a cavity therein, said cavity having an open end disposed adjacent to said partition.

In testimony whereof, I hereunto affix my signature.

ARTHUR E. SMITH.
